JAY H. HALL, OF CLEVELAND, OHIO, ASSIGNEE TO THE ELECTRIC CONTROLLER AND MANUFACTURING COMPANY, OF CLEVELAND, OHIO, A CORPORATION OF OHIO.

MOTOR-CONTROL SYSTEM.

1,122,743.

Specification of Letters Patent. Patented Dec. 29, 1914.

Application filed September 5, 1913. Serial No. 788,278.

To all whom it may concern:

Be it known that I, JAY H. HALL, a citizen of the United States, residing at Cleveland, in the county of Cuyahoga and State 5 of Ohio, have invented new and useful Improvements in Motor-Control Systems, of which the following is a specification.

My invention relates to control systems for electric motors, particularly to systems 10 in which the motor circuit passes through the contacts of an operator's switch and is automatically controlled by a plurality of magnetically-operated switches. More particularly, it relates to systems in which the 15 operating windings of the magnetically-operated switches are energized by the current in the motor circuit.

One of the objects of my invention is to control at will the variation of the resistance 20 of the motor circuit in combination with the automatic removal of the resistance by means of the magnetically-operated switches.

A further object of my invention is to 25 enable the operator to cause the switches to open and insert the resistance in the motor circuit without producing any arcing at the switch contacts.

Other objects and advantages of my form 30 of control system will be hereinafter described.

In the accompanying drawings, Figure 1 is a diagrammatic representation embodying the system of my invention. Fig. 2 is 35 a modification showing another form of my invention.

Referring to the drawings, the motor to be controlled is shown with the armature A and the series field winding F.

The resistances for controlling the motor circuit are indicated at R', R², and R³. The resistances are arranged to be automatically controlled by the switches S', S², and S³, having operating windings C', C², and C³ 45 arranged to be connected in the motor circuit. I prefer to use for these switches the type of switch disclosed in Eastwood's Patent, No. 1,040,292, which remains open when the current in its winding is above a predetermined value, and operates to close its contacts when the current is reduced. The operator's switch, shown at M, in Fig. 1 and at N in Fig. 2, has stationary and movable contacts by which the operator can vary at 55 will the motor circuit connections.

I will first describe the operation of the control system shown on Fig. 1. When the operator moves the switch M to the position 1, the motor circuit is as follows: From the positive through the contact finger 12, the controller contacts, the contact finger 11, the winding C' of the switch S', the resistances R', R², and R³, the armature A, and the field F to the negative. All the starting resistances are included in the motor circuit and the motor operates at its slowest speed. If the motor current exceeds a predetermined value, the switch S' will remain open until the current has reduced sufficiently to allow the switch to close. When the current has reached this value, the switch S' closes but does not cause any of the resistance to be removed from the motor circuit so long as the operator maintains the switch M in position 1. In other words, as long as the switch M remains in position 1 the resistance in the motor circuit will remain at its maximum value. If the operator moves the switch to position 2, after the switch S' has closed, the motor circuit will then be as follows: From the positive through the contact finger 12, the controller contacts, the contact finger 11, the winding C', the contacts of the switch S', the contact finger 10, the controller contacts, the contact finger 9, the winding C² of the switch S², the resistances R² and R³, the motor armature A, and the field F to the negative. The resistance R' has been cut out and the winding C² energized, the switch S' remaining closed. If the current of the motor circuit exceeds the value at which the switch S² is adjusted to operate, this switch will remain open until the current diminishes, whereupon it will close its contacts. This will not cause further resistance to be cut out until the operator moves the switch to position 3. With the operator's switch in position 3, the resistance R² is cut out and the winding C³ of the switch S³ is energized, the switches S' and S² remaining closed. The switch S³ remains open until the current diminishes below the value at which this switch is adjusted to operate, whereupon it will close its contacts. When the switch M is moved to position 4, the resistance R³ will be cut out and the motor will then operate at its maximum speed. The motor circuit at this time will be as follows: From the positive through the contact finger 12, the controller contacts, the contact finger 11, the winding C³ of the switch S³, the motor armature A, and the field F to the negative.

- contacts, the contact finger 11, the winding C', the contacts of the switch S', the contact finger 10, the controller contacts, the contact finger 9, the winding C², the contacts of the switch S², the contact finger 8, the controller contacts, the contact finger 7, the winding C³, the contact finger 5, the contacts of the controller, the contact finger 6, the contacts of the switch S³, the motor armature A, and the field F to the negative.
- 10 In moving the operator's switch M back toward the off position the contacts at the successive steps open the circuit through the contacts of the switches S³, S², and S', respectively, before the windings of the said switches are deenergized and the said switches are opened, wherefore the said switches drop open, at a time when no current flows through their contacts, thus preventing any arcing at the same. If the operator's switch is moved from the off position immediately to position 4, the switches S', S², and S³ will close in automatic progression to cut out the starting resistance, each switch in closing energizing the winding of the succeeding switch and each switch remaining open until the current in the motor circuit has diminished to a predetermined value.
- 15 In Fig. 2 the starting resistances R', R², and R³ are arranged for parallel connection instead of the series connection of Fig. 1. When the operator's switch N is moved to position 1, the motor circuit is as follows:
- 20 From the positive through the contact finger 18, the controller contacts, the contact finger 17, the winding C', the resistance R', the motor armature A, and the field F to the negative. This is the position of maximum resistance and as long as the operator's switch remains in position 1 the motor operates at its slowest speed. If the motor current exceeds the predetermined value, the switch S' remains open. It closes its contacts when the motor current is reduced to the said value. When the operator wishes to increase the speed of the motor, the switch N is moved to the position 2, whereupon the motor circuit is from the positive through the contact finger 18, and the controller contacts, the contact fingers 17 and 16 in parallel, one branch of the circuit being through the winding C' and the resistance R' and the other branch being through the contacts of the switch S', the winding C² and the resistance R² to the point where the branches unite, the united circuit being thence through the armature A and the field F to the negative. The switch S² remains open until the current in its winding has diminished to the value at which it is adjusted to operate, whereupon the switch S² closes. To increase the speed of the motor further, the operator's switch N is moved to position 3, whereupon a third branch of the circuit is
- 25 made through the contacts of the switch S², the windings C³, and the resistance R³. The three branches of the motor circuit through the resistances R', R² and R³ all carry current, depending upon the values of the resistances. The switch S³ remains open until the current through its winding C³ is diminished to the value at which it is adjusted to operate, whereupon it closes.
- 30 When the operator moves the switch to position 4, all the resistance is cut out and the circuit is then from the positive through the contact finger 18, the controller contacts to the contact finger 14, the contacts of the switch S³, the motor armature A, and the field F to the negative. The windings C', C² and C³ will be deenergized and the switches S' and S² will drop to their open positions. To maintain the switch S³ closed, a holding winding C⁴ is provided which is energized from the contact 13 on the operator's switch. This holding winding is so designed that it will not cause the switch S³ to close but will hold it closed after the switch has been closed by its operating winding C³. The speed of the motor can be decreased by moving the operator's switch back to the intermediate positions 1, 2, and 3, or the motor can be stopped by moving it to the off position, as shown in the drawing. A series holding winding can be substituted for the shunt winding C⁴ on the switch S³ if desired. The series winding in such an arrangement may be connected in the conductor 19 and would not become energized until the closure of the switch S³ with the operator's switch in position 4. It will be noticed that, in moving the operator's switch from any of these positions toward the off position, the circuits through the switch contacts are opened before the operating windings of these switches are deenergized so that there is no arcing at the switch contacts, and that the resistance is removed from the motor circuit only when the current in the motor circuit is below a predetermined value and that the operator can delay the cutting out of the resistance at will.
- 35 It will be understood by those skilled in the art that a reverser may be provided for the motor if it is desired to reverse the motor. It will also be obvious that other changes can be made in the apparatus without departing from the spirit of my invention.
- 40 I claim—
1. In a circuit-varying controller, a controlled circuit, resistances, a series of switches for cutting out the resistances, operating windings therefor energized by current in the controlled circuit, and means for deenergizing the said windings at will.
- 45 2. In a current-varying controller, a controlled circuit, resistances, a series of

switches for cutting out the resistances, operating windings therefor energized by current in the control circuit, and means for progressively energizing and deenergizing 5 the said windings at will.

3. In a current-varying controller, a controlled circuit, resistances therefor, a series of switch contacts for the resistances, operating windings for the switch contacts 10 adapted to be connected in the controlled circuit, sets of contacts corresponding to, and adapted to be put in series with, the said switch contacts, and means for closing one or more of the said sets of contacts at 15 will.

4. In a current-varying controller, a controlled circuit, resistances therefor, a series of magnetically-operated switches for cutting out the resistances, operating windings 20 therefor, and an operator's switch comprising contacts for consecutively connecting said switch windings in the controlled circuit.

5. In a current-varying controller, a controlled circuit, resistances therefor, a series of switches for automatically cutting out the resistances, operating windings therefor energized by current in the controlled circuit, and an operator's switch for delaying 25 the operation of the switches, comprising contacts for connecting the winding of the first switch in series with the resistance and for connecting the contacts of the first switch in series with the winding of a second switch of the series.

6. In a current-varying controller, a controlled circuit, resistances therefor, a series of switches for automatically cutting out the resistances, operating windings therefor 40 energized by current in the controlled circuit, and an operator's switch having contacts in the controlled circuit for connecting the contacts of each switch in a circuit including the winding of the next succeeding switch.

7. In an electric motor-control system, a motor, resistances, a series of magnetically-operated switches having contacts for controlling the resistances, and an operator's switch having contacts in series with the 50 switch contacts for progressively opening and closing the circuit at will through the said switch contacts.

8. In an electric motor-control system, a motor, resistances, a series of magnetically-operated switches having contacts for controlling the resistances, and an operator's switch having contacts in series with the 55 switch contacts for progressively opening the circuit through the said switch contacts.

9. In a motor-control system, a motor, a circuit therefor, a plurality of resistances in the circuit, a series of switches for controlling the resistances, operating windings therefor energized by current through the 60 motor, and an operator's switch comprising contacts for connecting the winding of the first switch in series with the resistances in the motor circuit and for shunting a portion of the resistances and connecting the 65 winding of the second switch in series with the winding of the first switch and the remaining resistances.

10. In a motor-control system, a motor, a circuit therefor, a plurality of resistances 70 for the circuit, a series of switches for controlling the resistances, operating windings therefor energized by current in the motor circuit, and a switch mechanism having contacts in the said circuit for connecting the 75 motor in circuit with maximum resistance, for preventing automatic variation of the resistance by the switches, and for permitting the switches to cut out the resistance.

Signed at Cleveland, Ohio, this 2nd day 80 of Sept., A. D. 1913.
